UNITED STATES PATENT OFFICE.

ALFRED E. JURY, OF NEWARK, NEW JERSEY, ASSIGNOR, BY MESNE ASSIGNMENTS,
TO MORGAN & WRIGHT, OF DETROIT, MICHIGAN, A CORPORATION OF MICHIGAN.

STRAIN-RESISTING ELEMENT FOR RUBBER ARTICLES.

No Drawing.

Application filed October 16, 1918. Serial No. 258,429.

To all whom it may concern:

Be it known that I, ALFRED E. JURY, a citizen of the United States, residing at Newark, county of Essex, State of New Jersey, have invented certain new and useful Improvements in Strain-Resisting Elements for Rubber Articles, of which the following is a full, clear, and exact description.

This invention relates to threads or cords, generically termed "strain-resisting-elements," for incorporation with rubber into articles that are completed by vulcanization, such, for instance, and particularly, pneumatic tire casings. The elements may be incorporated either individually or collectively in the form of cord, woven, or weftless, fabric. The objects of the invention among others appearing later are to improve the structure of the strain-resisting-elements over what has heretofore been employed and to reduce the cost of their manufacture.

My invention is not restricted to any particular kind of fibre, but for the purpose of illustration it will be described in connection with threads, cords, and the like made from cotton. In the usual manufacture of cotton thread, cords, etc. the cotton from the bale is loosely opened out and subjected to a course of treatment directed to the removal of the shorter staple, leaf, and other foreign matter, and to the placing of the fibres into substantially parallel directions and to finally drawing out the fibres thus arranged into a uniform strand termed roving. The roving has a very slight twist imparted to it in order to make sure of its maintaining its uniformity and parallelism during the subsequent processes which it must be subjected to in order to produce the final cord.

The roving having no appreciable twist, the fibres composing it are in such loose contact there is little or no friction between them and consequently there is no appreciable tensile strength. In order to produce the required frictional contact and consequent tensile strength the usual practice is to draw the roving, which is of comparatively large cross-section, out into a fine filament and to spin it into what is termed a single yarn. A number of these yarns are then twisted together to form a plied yarn and finally a number of the plied yarns are twisted together to form the cord.

The forming of the single yarn requi-

much time and expensive machinery and is in fact the most costly operation in the manufacture of cord. For instance in the manufacture of cord fabric for forming the plies of pneumatic tires for motor vehicles the single yarn is usually formed by drawing out the roving about ten times its length and simultaneously giving this finely drawn filament a twist of between fifteen to twenty turns per inch of length. Five of these single yarns are then twisted together to form a plied yarn, and three of the plied yarns are finally twisted together to form the cord. These two twisting operations require much less time and expense than does the formation of the yarn, for the slow and delicate drawing operation is not present in the latter operations.

The cord thus formed has the cotton fibres very tightly spun together in the formation of the yarn and then further bound together by the two subsequent processes of twisting the single yarns. The fibres are thus self-retained together with a degree of permanency that well adapts the cords for the general wear and tear of service tending to loosen the fibres. This, however, involves the necessity, after having carefully formed the roving of uniform cross-section composing a relatively large number of parallel fibres, of then taking the backward steps of drawing the roving out until it is reduced in cross-section to a mere thread composed of a comparatively few fibres, and then combining a number (fifteen) of these yarns together until the cord is again enlarged in section to the desired size to give the required strength.

It will therefore be seen that if the roving can be used as originally formed, that is to say without resorting to the backward steps of drawing out and then plying up, a material saving will be attained in time and expensive apparatus employed. Moreover the tightly spun yarn and the plying of the same together by twisting, so tightly holds the fibres together that the cord is not of the desired degree of pliability to withstand the required flexing that is necessary for the many uses to which the cords are put and therefore the tightly held fibres are weakened by repeated flexing and prematurely break.

I have discovered that a cheaper and

more desirable strain resisting element for vulcanized rubber articles, such as tires, may be manufactured from the rovings direct without substantial attenuation thereof merely by loosely twisting them together.

According to my invention, I take the ordinary roving after it has been attenuated as usual on draft rolls to a diameter of approximately $\frac{1}{16}$ or $\frac{1}{8}$ of an inch and before it has been spun and further attenuated, and loosely twist a plurality of these rovings together, thus making a soft pliable cord or warp yarn.

Without intending to limit myself and by way of example, a satisfactory tire fabric may be made with cords or yarns from 4 rovings of between $\frac{1}{16}$ and $\frac{1}{8}$ of an inch thick twisted together 8 times to an inch. The number and size of the rovings and the amount they are twisted together may, of course, be varied within wide limits, the essential idea being the utilization of unspun and substantially untwisted fibrous rovings as the base of a strain resisting element for vulcanized rubber articles.

The cord or warp yarns may be built into the rubber articles before curing as thus completed or they may be woven into fabrics or otherwise rendered manipulatable for incorporation in rubber articles. They may be utilized for both the warp and weft threads of a plain woven fabric, or as the warp threads of what is known as cord fabric. The latter is largely used in the manufacture of tires and consists of close lying warp threads held together by fine filling threads of say No. 20 at intervals of $\frac{1}{8}$ of an inch. The weft threads of cord fabric for tires may be made as fine as desired and their spacing may be varied, the sole function of these filling threads being to hold the cords together during the subsequent manipulation of the fabric. Obviously also, the cords or warp yarns in close parallel relation may be united by intermediate webs of rubber connecting them and forming what is called "weftless fabric."

Whatever form the cord or warp yarn may be put into for incorporation in the rubber article, the next step is to bind its fibres together with one or more coats of rubber or a vulcanizable rubber composition. This may be done in any suitable manner as by the usual friction or skim coating methods. Without a binding material the fibres of the several unspun and loose rovings composing the strain resisting elements are easily disarranged when subjected to abrasion. While in their bare or uncoated condition the warp threads or yarns are therefore commercially useless, it has been discovered that they function very satisfactorily as strain resisting elements when imbedded in rubber composition and vulcanized. The loose fibres of the rovings in each

element seem to be held in their loose relation without liability of abrasion on one another and the elements possess the requisite tensile strength. At the same time they are more flexible and less liable to heat than previously used hard twisted cords or strain resisting elements.

It is obviously not essential that the binding material, relied upon to give permanency to the twists of the cord, be applied to the cords individually for in many cases, such for instance as the manufacture of pneumatic tires, the cords may be woven into cord fabric or the usual fabric, or otherwise combined, and the twisting of the strands together may be relied upon to impart sufficient permanency to the cord to permit of such and similar manipulation, so that after the cords have been formed into a fabric or otherwise formed into a layer or ply they may be treated with the binding rubber in any of the usual or preferred ways of rubber coating fabric. It is also obvious that some degree of twist may be given to the individual strands if desired providing this does not materially detract from the flexibility of the cord and also that one or more strands without twist may be combined with one or more twisted strands, or yarns, or plied yarns, making what may be termed a combination cord. It is also within the spirit of my invention to twist a single strand, element or roving which may be of enlarged cross-section until a maximum tensile strength consistent with maximum flexibility is attained and then associating the strand thus formed with a binding material in any of the ways above described. As therefore many apparently widely different embodiments of the invention may be made without departing from the spirit thereof, it is to be understood that I do not intend to limit myself to the specific form of the invention as set forth except as indicated in the appended claims.

Vulcanized rubber articles having strain resisting elements of the character above specified are more pliable and durable and are less expensive than previously known elements for the same purpose. The soft non-compacted arrangement of the fibres in the cords diminishes their abrasive or cutting action on one another and lessens the heating. These last named features are highly desirable in tires, blow-outs being attributed to fibre cutting and heating being ascribed to the rubbing of the fibres upon one another. The strain resisting elements of the present invention require less fibrous material to furnish the required tensile strength than prior cords or warp yarns, shorter staple cotton may be used, and in their manufacture expensive and time consuming operations are eliminated. In short, the present invention provides a better strain

resisting element for vulcanized rubber articles at less cost.

Having thus described my invention what I claim and desire to protect by Letters Patent is:

1. A fabric reinforcement for rubber tires having strain resisting elements consisting of a plurality of unspun rovings twisted loosely together.
- 10 2. A vulcanized rubber article the strain resisting elements of which consist of loosely twisted fibres.
3. A vulcanized rubber article the strain resisting elements of which consist of a plu-

rality of soft fibrous strands twisted loosely together.

4. A vulcanized rubber article the strain resisting elements of which consist of a plurality of substantially untwisted rovings.

5. A vulcanized rubber article the strain 20 resisting elements of which consist of a plurality of unspun rovings twisted loosely together.

Signed at New York, county of New York, State of New York, this 11th day of October, 1918.

ALFRED E. JURY.
